HIS ATTORNEYS.

UNITED STATES PATENT OFFICE.

DANIEL C. STOVER, OF FREEPORT, ILLINOIS.

SPRING-HINGE.

SPECIFICATION forming part of Letters Patent No. 391,433, dated October 23, 1888.

Application filed February 20, 1888. Serial No. 264,622. (Model.)

To all whom it may concern:

Be it known that I, DANIEL C. STOVER, a citizen of the United States of America, residing at Freeport, in the county of Stephenson and State of Illinois, have invented certain new and useful Improvements in Spring-Hinges, of which the following is a description, reference being had to the accompanying drawings, in which—

10 Figure 1 is a face view, and Fig. 2 a rear view, of a spring-hinge containing my improvements. Fig. 3 is a detail view of the same when the spring is "let down" and exerting its tension on one leaf alone. Fig. 4 is 15 a detail view of the same in a position intermediate between those shown in Figs. 1 and 3. Fig. 5 is a detail view of the collar B, and Fig. 6 is a detail cross-section showing the arrangement of the collar B.

20 The object of my invention is to provide a spring-hinge which by a simple adjustment may be converted into a simple hinge without spring-resistance to its opening or closing, and which can be as readily reconverted into a 25 spring-hinge again.

I have devised a simple device whereby the spring to which it is applied can be transformed to and from a simple hinge without "unwinding" the spring and without material change in its tension.

30 My invention consists in attaching one end of the spring in a spring-hinge to a collar or ring provided with a projection or stop having an inclined or cam surface, and which may be made to engage against either of the leaves of the hinge, as will be hereinafter more particularly described.

35 In the drawings, A A' are the leaves of a hinge united by the ears a a' in any appropriate manner. The usual coiled spring, C, is inserted in the hinge, with one end, c', bearing against one of the leaves A', and with the other end, c, rigidly attached to the ring or collar B, mounted upon the pintle or pin running through the adjacent ear a'. The collar B is provided with the cam-shaped projection or stop b, which projects sufficiently to bear upon its rear or vertical side against the rear edge of the leaf A', as shown in Fig. 3. The 40 spring is inserted in this position under substantially the full tension required; but as both the projection b at one end of the spring and the end c' at the other end of the spring bear against the same leaf A' the leaves may 45 be opened and closed, as in a simple hinge,

50 without any spring-resistance. The other leaf, A, however, is provided with a notch or projection, a², and the collar B with means for revolving it. In the form illustrated in the drawings this is a hole, notch, or recess, b', 55 into which a nail or pin can be inserted to turn it.

When it is desired to convert the hinge into a spring-hinge, it is only necessary to give the collar B a partial turn or revolution, when 60 then cam side of the projection b rides under the notch a², compressing the spring axially, as shown in Fig. 4, until the stop b has passed the stop a², when the axial tension of the spring brings the stops into engagement, as 65 shown in Figs. 1 and 2. The radial tension of the spring has thus been changed at its upper end from the leaf A' to the leaf A, so that the 70 spring now bears equally against the opposite leaves, converting it into a spring-hinge. It 75 is reconverted into a simple hinge without spring-resistance by simply pressing the projection b downward, as shown in Fig. 4, when it passes around again to a bearing against the rear edge of the leaf A', as shown in Fig. 3. 80 It is obviously immaterial whether the inclined or cam surface be on the stop b or its corresponding stop a². This inclined or cam surface upon the stop contributes materially to the convenient working of the parts, and is 85 an important element in my invention.

The hinge described is of the simplest possible form, cheap in construction, and durable and effective in operation.

Having thus described my invention, what I 90 claim as new, and desire to secure by Letters Patent, is—

In a spring-hinge, the combination of the leaves with a coiled spring, one end of which is connected with one leaf and the other end 95 of which is attached to an adjustable collar mounted adjacent to one of the inner ears of the hinge and provided with a cam-shaped stop bearing alternately against either of the leaves of the hinge, whereby the radial tension 100 of the spring is applied wholly to one leaf of the hinge, or may be changed to apply equally against both leaves, and whereby such change in the adjustment is effected by the mere rotation of the collar, substantially as 105 described.

DANIEL C. STOVER.
